UNITED STATES PATENT OFFICE.

BENJAMIN B. KEYES, OF CHELSEA, ASSIGNOR OF ONE-HALF OF HIS RIGHT
TO JOHN S. POTTER, OF NEWTON, MASSACHUSETTS.

ELEVATOR.

SPECIFICATION forming part of Letters Patent No. 226,077, dated March 30, 1880.

Application filed July 30, 1879.

To all whom it may concern:

Be it known that I, BENJAMIN B. KEYES, of Chelsea, in the county of Suffolk and State of Massachusetts, have invented certain new and useful Improvements in Elevators, of which the following is a specification.

My invention relates to that class of elevators in which the car or platform is raised or lowered by means of one or more ropes wound upon a drum, the rotation of which winds or unwinds the rope or ropes, and thereby raises or lowers the car or platform.

The objects of my invention are to prevent accidents occurring by overloading the car or from the breaking of the ropes, belts, pulleys, or other portions of the elevator mechanism, which will permit the car or platform to fall at a higher or greater rate of speed than designed; and it consists in the construction, combination, and arrangement of a safety-wheel with the main or drum shaft of the elevator, whereby, if the speed from any cause should exceed the speed designed, or if said shaft and wheel should attain a greater number of revolutions per minute, a centrifugal weight will be brought in contact with certain mechanical devices, so as to operate the shipper instantly and guide the belt upon the loose pulley, thereby stopping the descent of the platform or car; and it further consists in the construction, combination, and arrangement of coiled steel or other springs with the main shaft, which has longitudinal movement imparted to it in case the car or platform should be overloaded, such springs thereby yielding or compressing sufficiently to allow longitudinal movement of the main or driving shaft to operate mechanism so as to ship the belt upon the loose pulley, and thus prevent the movement of the car or platform in either direction until the overload or extra weight shall have been removed therefrom, thereby operating as a safety-guard in case of any mistake as to the extreme weight designed to be carried or when the weight of the load is underestimated; and it further consists in certain details of construction hereinafter more fully described and set forth.

Figure 1 shows a perspective view of an ele-

vator constructed according to my invention. 50 Fig. 2 is a similar view of the reverse side of the same. Fig. 3 is a similar view of one end of the same. Fig. 4 is a longitudinal vertical section taken through Fig. 1. Fig. 5 is a plan view of the driving-shaft, pulleys, and belt-shipping mechanism. Fig. 6 is an elevation of a portion of the belt-shipping mechanism detached. Fig. 7 is a perspective view of the belt-shipping mechanism, showing both devices. Fig. 8 shows an end elevation of a portion enlarged and detached from Fig. 3. Fig. 9 shows a perspective view of a portion enlarged and detached from Fig. 3.

A represents the bed of the elevator, provided at one end with the journal bearing or 65 box B, and at the opposite end with the journal-bearing B', and about midway with the bearing B''. Within these bearings are placed the main driving-shaft H, provided with loose pulleys C C' and fixed pulley D, and brake-wheel D', and the screw or worm-gear E meshing into the main gear-wheel F, which is permanently connected to the rope-drum G, as usual.

Connected to the top of the car or platform 75 by one end is a wire rope or ropes, (not shown,) and connected at the other end to the drum G, so as to be wound upon the same when the car or platform is to be elevated to the various floors of a building, and unwound therefrom 80 when the same is to be lowered by movement of the shipper-wheel Z, which is actuated by the shipper-rope I, which passes through the elevator well-hole from top to bottom, and through or near the car or platform, so as to 85 enable the operator to ship either the straight or cross belt from the loose pulleys C or C' to the driving-pulley D, so as to carry the car or platform up or down, as desired, in the manner heretofore.

Now, in order to prevent the car or platform being overloaded, so as to endanger the breaking of the suspension-ropes, I have provided automatic shipping mechanism, which is actuated by longitudinal movement of the main 95 shaft H, which has a bearing at one end upon a steel disk or friction-plates, a, one of which contacts with the end of the coiled steel spring

b, which is compressed within its socket c when the weight of the car or platform is suspended by the rope wound upon the drum G; but in case the weight of the car or platform 5 is removed therefrom through any cause the spring b will elongate, so as to force the main driving-shaft H back longitudinally, and thereby operate the shipping mechanism so as to stop the drum, as hereinafter described; and 10 in case the weight placed upon the car or platform should be excessive or more than can be elevated with safety the socket c will be forced against the plate d, which has a bearing upon the ends of the coiled steel springs e e, which 15 are supported in position at the end of the bed A by screw-bolts f f, which pass through the same and within the springs e e, and are secured by nuts g g bearing upon the plate h, as shown in Fig. 5.

20 At about mid-length of the main shaft H is secured a disk or wheel, i, which revolves within the bifurcated end of the lever k, pivoted to the bed A, and provided with several holes, into one of which is secured the vertical standard n, upon the upper end of which rests the horizontal weighted arm l, the opposite end of which is connected to a socket-piece supporting double spring-pawls r, which engage with the teeth of the ratchet o, secured 25 to the horizontal rod s, which has secured to its opposite end the vertical shipper t, the upper end of which has contact within the groove u, formed in the periphery of the hub v of the loose gear J, which is driven by 30 to the horizontal rod s, which has secured to its opposite end the vertical shipper t, the upper end of which has contact within the groove u, formed in the periphery of the hub v of the loose gear J, which is driven by 35 the gear W, keyed upon the shaft N, and which is provided upon its inner face with a clutch-gear or teeth, m, which engage with similar teeth upon the outward face of the gear K, keyed upon the shaft L, journaled in 40 the upright supports A'. This gear K connects with the loose gear M upon the shaft N, also journaled in the supports A', and which shaft N also carries the main large gear-wheel F, connected to one side of the rope-drum G, 45 and which is driven by the screw or worm-gear E upon the main shaft H.

Thus it will be seen that when the loose gear J is actuated so as to engage with the gears K and M motion is communicated to the shipper-wheels P, so as to cause their teeth w to slide the shipper-rack bars R, and thus ship the belt upon the loose pulley C, and thus prevent the car or platform being elevated until a portion of the load has been removed, so as to 50 allow the main shaft H to revolve in that position designed for safety when the elevator is in operation.

Now, in order to provide a safety-guard against accidents occurring by too great speed 55 being given to the main shaft H and elevator through any cause, I have provided such shaft with a safety-wheel, Q, which has connected to its periphery a centrifugal weight, S, which is held in its normal position by a steel spring, T, connecting the same in such manner that

when the said wheel G shall attain a greater number of revolutions per minute than is designed for safety the said weight S will, by its momentum, act upon the spring T so as to project itself farther from the periphery of the 70 wheel G, and thereby come into contact with the end of the horizontal adjustable screw-bolt U, which projects from the vertical hinged standard V, and thus force it out of position, so as to let fall the weighted arm p, connected 75 to a socket-piece supporting the double spring-pawls r', which engage with the teeth of the ratchet o', secured to the horizontal rod s, as shown in Fig. 6, so as to actuate it, and thus operate the shipping mechanism as before described in the operation of the longitudinal movement of the main shaft H.

In order to insure a uniform relative position to be maintained between the teeth x upon the shipper rack-bars R and the teeth w 85 upon the shipper-wheels P, I form the teeth w with their extreme ends one-eighth of an inch greater radius than the periphery of the said wheels P, upon which they are formed, and further provide rectangular shoulders j, which 90 contact with the outer surfaces of the two outer teeth, x, upon the shipper rack-bars R, these with the peculiar curves x' extending each side of the said teeth, as shown in Fig. 9, and which contact with a portion of the 95 wheels P at each side of their teeth w as the shipper rack-bars R slide back and forth in the operation of shipping the belts in all cases.

It will be obvious that a weight or weights may be substituted for the coiled steel springs 100 e e, and thus serve the same purpose as contemplated by that part of my invention, and that springs may be connected with the ends of the arms l and p in such manner as to accomplish the same result as with the weights 105 shown attached thereto, and, as such changes and others of a similar nature are well-known mechanical equivalents, I will not describe such more in detail.

Having thus described my invention, what I 110 claim is—

1. In combination with the main shaft H, the friction-plates a, spring b, sockets c, plates d and h, and springs e, adapted to allow horizontal movement of said shaft, whereby the 115 shipping mechanism is operated automatically, as and for the purposes set forth.

2. In combination with the main shaft H, the wheel i, bifurcated lever k, standard n, horizontal arm l, double spring-pawls r, and 120 ratchet o, connected with the rod s, so as to operate the shipping mechanism automatically by the horizontal movement of the main shaft H, as and for the purposes set forth.

3. In combination with the main shaft H, 125 the safety-wheel Q, having the self-adjusting centrifugal weight S, the horizontal adjustable screw U, vertical hinged standard V, arm p, double spring-pawls r', and ratchet o', connected with the rod s, so as to operate the 130

shipping mechanism automatically by the speed of the main shaft H, as and for the purposes set forth.

4. The extended teeth *w* upon the shipper-wheels P, having the corners *j*, in combination with the shipper rack-bars R, having the peculiar curves *x'* shown, so as to prevent

irregular movement between the said wheels P and rack-bars R, as and for the purposes set forth.
